UNITED STATES PATENT OFFICE.

FELIX RIESENBERG, OF NEW YORK, N. Y., ASSIGNOR TO MAUD C. RIESENBERG, OF NEW YORK, N. Y.

SHAVING-STICK AND THE LIKE.

1,194,427.

Specification of Letters Patent. Patented Aug. 15, 1916.

Application filed October 28, 1914. Serial No. 369,135.

To all whom it may concern:

Be it known that I, FELIX RIESENBERG, a citizen of the United States, residing in the borough of Queens, county of Queens, city of New York, State of New York, have invented certain new and useful Improvements in Shaving-Sticks and the like, of which the following is a full and clear specification.

- 10 My invention relates in general to devices, such as shaving sticks and their receptacles and is applicable to other articles which are handled or used in more or less the same way, that is to say, by a rubbing or action 15 which results in a gradual wearing away of the material applied. Numerous examples of such substances might be cited, and for illustration I may refer to medicinal articles, such as menthol pencils, alum and 20 similar pencils, lubricating sticks, such as graphite, buffing and polishing materials, such as rouge and like compositions and coloring sticks, such as charcoal, crayons, and the like. While my invention is thus 25 not limited to its embodiment in the form of a shaving stick device, this class of articles is one which is perhaps more generally known than the others and I shall, therefore, refer to the device as a shaving stick 30 in the following specification and claims, it being understood that the other articles of the character mentioned are equivalents and meant to be included as embraced by the invention.
- 35 It has heretofore been proposed to form shaving sticks in cylindrical or other form and inclose them in one way or another in a cylindrical box of metal, or the like. The box comprises a body portion and removable cover or cap. In some forms of these 40 previously known devices the shaving stick has been provided at one end with a band or cap, which may form a portion of the box referred to or which serves as a means for 45 securing the shaving stick to the main body of the box. The shaving sticks heretofore known are of such size and dimensions that their entire consumption involves a considerable period of time and before they are 50 entirely used up the soap becomes dry and hard, and thus the soap loses certain of its desired properties or qualities. The cleanliness of the stick is frequently affected by
- constant handling and use and the attractive appearance of the new article is soon 55 lost. Furthermore, the previously known shaving sticks have not always been convenient to handle, due to their awkward length.
- The objects of my invention are mainly 60 to do away with the disadvantages above referred to in shaving sticks, and to provide a shaving stick device of the character mentioned in which the soap is retained in a cleanly, sanitary receptacle, conveniently 65 handled and presenting a neat attractive appearance. I attain these objects primarily by arranging the soap in a two part box or case with but one half of its length exposed at one time, the other half being effectively 70 sealed in what I may term the body portion or holder portion of the case. The soap is provided at about its middle portion with a band which is suitably formed to be removably secured in the open end of the 75 holder portion of the box. In this way approximately half of the soap is consumed while the other half is sealed in the holder portion after which the stick may be inverted for the use of the other half of the 80 soap. The holder portion is preferably flattened at the bottom, so as to stand and keep the exposed portion of the soap out of contact with foreign material. The upper half or cover portion of the case is preferably formed to snap on and off, or to be otherwise removably secured over the exposed portion of the soap, and in the embodiment hereinafter shown and referred to, 85 this cover portion snaps on to the central band which latter forms an intermediate portion of the box between the holder portion and the cover.
- An embodiment of the invention is illustrated by way of example in the accompanying drawing, in which—
- Figure 1 is an outside elevation of the assembled soap and case; Fig. 2 is a vertical section of the same; Fig. 3 is an elevation of the holder portion of the case with the soap 100 mounted therein, ready for use, and Fig. 4 is a detailed vertical section of the central portion of the soap showing an example of the band by which the soap is secured in the case, and Fig. 5 is a view, similar to Fig. 4, 105 of a slightly modified form of the invention.

Referring more specifically to said drawing, 10 indicates the holder portion of the case, provided with a flat bottom 11, by which the case is adapted to stand. Preferably the bottom 11 is somewhat expanded to facilitate handling and to enhance the appearance. The upper portion of the holder 10 is in the present instance threaded as indicated at 12 to receive the correspondingly threaded band which encircles the soap. The band preferably comprises two threaded halves 13 and 14, as indicated in Fig. 4, spun together with an intervening backing or diaphragm 15 of cardboard or the like. The two halves 16, 17 of the soap are in this instance pressed into the band 13, 14 against the diaphragm 15 and caused to expand into the threaded portions and thus be firmly secured. It will be understood that the use of the diaphragm 15, and the formation of the band in two sections is optional, these features having been illustrated as showing a construction which is easily carried out in practical manufacture. The diaphragm 15 furthermore is useful in providing the equality of length in the two ends of the stick, and furthermore is effective in sealing the reserve portion of the soap and preventing its dislodgment. The diaphragm 15, may, however be left out altogether in the case that a single stick of soap 16^a should be used. This modification is illustrated in Fig. 5. The two halves 13 and 14 of the band are, as above referred to, spun together. The spun over portion 18 of one half of the band forms a medial rim and is preferably milled or knurled as indicated, to facilitate the introduction and removal of the stick in the holder 10 while at the same time forming a positive stop for the two halves of the case and presenting a neat appearance. The upper or cover portion of the case is indicated at 19 and in general dimensions may be approximately equal to the holder portion 10 of the case. The top of the cover is preferably rounded as indicated at 20, so as to distinguish the two portions of the case in use. The cover 19 is suitably secured in place as, for example, by means of impressions 21, which snap over the threads of the band.

It will be observed by reference to Figs. 1 and 2 of the drawing that the two portions 10 and 19 of the case do not actually contact with each other. I wish to point out that while I do not intend that the invention should be limited to a construction in which the two halves of the case are secured together by engagement with a third member interposed between them, still I do regard this feature as a specific element of invention and prefer to form the case and band so as to coöperate together in this way, as the insertion and reversal of the soap within the holder is greatly facilitated by the prominence of the band and furthermore the positive stop thus provided for the soap and the two portions of the case, is a feature of practical convenience and utility.

While I regard the wrapping of the ordinary shaving stick in tin foil or the like, to preserve it, as an inefficient and inconvenient expedient, it will be apparent that in the present instance the wrapping of the two portions of the soap may still be carried out, without interference with the general principles and operation of my invention. The location of the band 13, 14 at the central zone of the soap, with the consequent subdivision of the case 10, 19, into two halves of approximately equal dimensions, not only provides the conditions referred to in connection with the use and preservation of the soap itself, but at the same time involves a material saving in the drawing operations performed in producing this style of case, rather than one in which substantially the entire depth is made up of a single piece of metal. It will be seen that in effect the two halves of the soap constitute a single bar, secured at its middle zone in the band which is invertibly mounted in the open end of the holder portion 10 of the case, the projecting portion of the soap being inclosed by the cover portion 19 of the case when not in use.

I claim:

1. A shaving stick device comprising in combination a bar of soap, a band permanently secured to the said bar of soap substantially midway between its two ends, and a case having a holder portion adapted to invertibly receive and engage said band at the open end of said holder portion.

2. A shaving stick device comprising in combination a bar of soap, a band permanently secured about said bar of soap approximately midway between the two ends thereof, a case having a holder portion adapted to invertibly receive and engage said band at the open end of said holder portion, and a removable cover portion adapted to inclose the projecting portion of the bar of soap.

3. A shaving stick device comprising in combination a bar of soap, a band having an external medial rim and surrounding an interior zone of the bar of soap with portions projecting to either side of the band and a case therefor comprising a holder portion adapted to invertibly receive and engage said band in its open end and inclose that portion of the soap projecting from one side of said band, and a cover portion adapted to inclose the other portion of said bar of soap and removably engage said band with said medial rim interposed between the two portions of the case.

4. A shaving stick device comprising in combination a two-part band with a diaphragm between the two parts, a two-piece

bar of soap having one portion seated in each side of said band against said diaphragm and projecting from the band, and a cup-shaped holder adapted to invertibly engage said band to inclose one of said bodies of soap and serve as a handle for the other.

5. A shaving stick device comprising in combination a band formed in two parts spun together to form a medial rim, soap fixed therein and projecting therefrom a substantially equal distance at either side, and a cup-shaped holder adapted to invertibly engage said band and seat against said medial rim.

10. A shaving stick device comprising in combination a band formed in two parts spun together to form a medial rim, soap fixed therein and projecting a substantially 20 equal distance at either side thereof, a cup-shaped holder adapted to invertibly engage said band and seat against said medial rim, and a cover adapted to engage the other side of said band and seat against said medial 25 rim.

15. A combined shaving stick holder and case formed in three parts, comprising a central ring adapted to receive and hold a shaving stick with both its ends protruding from the ring, and two end caps or covers engaging said central ring and inclosing the two ends of the soap stick.

20. A combined shaving stick holder and case formed in three parts, comprising a central ring adapted to receive and hold the shaving stick with both its ends protruding from the ring, and two end caps or cov-

ers engaging said central ring and inclosing the two ends of the soap stick, with means detachably securing the caps to the 40 ring.

25. A combined shaving stick holder and case formed in three parts, comprising a central ring adapted to receive and hold the shaving stick with both its ends protruding from the ring, and two end caps or covers engaging said central ring and inclosing the two ends of the soap stick, said ring being provided with peripheral fastening devices and said caps or covers being provided with complementary fastening devices 50 adapted to hold them in engagement with the ring.

30. As an improved article of manufacture, a stick of soap and a combined holder and case therefor formed in three parts, comprising a central ring secured on the soap stick and provided with oppositely extending screw threads, and two end caps, each provided with terminal screw threads 55 to engage the threads on said ring.

35. As an improved article of manufacture, a stick of soap and a combined holder and case therefor formed in three parts, comprising a central ring and two end caps, 60 the central ring having its open ends provided each with one element of a fastening pair, and the end caps each having its open end provided with a complementary fastening device.

FELIX RIESENBERG.
